CLOTHESLINE HANGER

Patrick J. Casserly, Cleveland, Ohio

Application February 21, 1939, Serial No. 257,687

2 Claims. (Cl. 211—96)

This invention relates to a clothesline support or hanger which is designed to be connected with or mounted on a wall, post or the like in a sheltered position and which may be swung outwardly when desired. In clothesline hangers or supports heretofore generally known, the usual difficulty encountered is that the clothesline must be stretched high enough to keep wet clothes from touching the ground; and if the line be stretched tightly, it is usually so high that it is difficult to reach, thus making a prop necessary.

One of the objects of my invention is to provide a clothesline hanger or support which is adapted to be pivotally mounted on a wall, post or side of a building in such a manner that it may be swung inwardly to a position where the clothes may be readily placed upon the line and then swung outwardly into the sun, the whole device being detachable and removable, if desired, when not in use.

A further object of the invention is to provide a clothesline hanger of the character described which requires no props and which is pivotally mounted so that the clothes may be swung outwardly into the sun or moved under a shelter in case of rain or a storm.

Another object of my invention is to provide a clothesline support or hanger which is rigid and dependable in operation and which consists of comparatively few parts which are well adapted for production at comparatively low cost.

Further and more limited objects of the invention will appear as the description proceeds and by reference to the accompanying drawing in which Fig. 1 is a top plan view showing my improved clothesline hanger as it will appear when attached to a suitable support, such as a corner of a building or porch; Fig. 2 is a view in side elevation of my clothesline hanger as it will appear when in one position; Fig. 3 is a vertical sectional view on the line 3—3 of Fig. 2; and Fig. 4 is a perspective view.

Referring now to the drawing, the device consists essentially of a bracket 1 preferably in the form of a casting which has a pair of outwardly projecting superposed spaced portions 2 and 3. The bracket 1 is secured to a suitable support such as the side wall of a building or post by means of suitable screws 4 and 5. Carried by the bracket 1 and pivotally and detachably secured thereto is a rod or pole 6 which may be in the form of a metal tube or formed from flat stock and is provided adjacent the outer end thereof with a flattened portion 7. The inner end of the pole is also flattened as shown at 6^a

and has an opening therein and extends between the outwardly projecting portions 2 and 3 and is secured thereto by means of a bolt 8 and a nut 9. Fitting over the bolt 8 are a pair of sleeves 10 and 11 the purpose of which will hereinafter appear. Secured to the pole 6, adjacent the inner end thereof, is a rod 12 to which is detachably secured a plurality of pins 13. Pivotally secured to the flattened portion 7 of the pole 6 is a rod 14 having detachably secured thereto a plurality of pins 15. The rod 14 is frictionally held in place by a pin or bolt 16 and is movable from a position shown in full lines in Fig. 1 to the position shown in dotted lines in said figure and serves to spread the clothesline 15 in a manner to be described hereinafter.

Secured adjacent the outer end of the pole 6 in any suitable manner is a rod 17 having detachably secured thereto a plurality of pins 18. Disposed adjacent the outer end of the pole 6 and extending at right angles to the rod 17 is a rod or tube 19 which is held in place by a pin 19^a. The opposite ends of the rod or tube 19 are slotted to receive a part of the clothesline therein. One section of the clothesline, which is indicated by the reference character 20, is stretched on the framework thus provided. This section of the clothesline is attached at one end to one end of the rod 12 and then stretched tightly over the pins 18 and thence over the pins 13, thence back over the pins 18 and back again to the rod 12, the spreader 14 being then in the position shown in dotted lines in Fig. 1. Another section of the clothesline, which is indicated by the reference character 21, has one end attached in a groove in the upper end of the sleeve 10 and is then stretched tightly over the rod 19 and attached at its opposite end to the end of the pole 6. Another section of the clothesline, which is indicated by the reference character 22, has one end attached to the lower end of the rod 19 and its opposite end attached to the grooved lower end of the sleeve 11. The clothesline hanger is secured in the position shown in Fig. 1 by means of a pin 22^a which extends through openings provided in the outwardly projecting portions 2 and 3 and the flattened end portion 6^a of the pole 6. The outwardly projecting portions 2 and 3 are provided with a pair of openings 23 and 24 which are brought into alignment when the clothesline hanger is moved to the outward position shown in dotted lines in Fig. 1. The hanger may be secured in this position by inserting the pin 22^a through these openings.

The clothesline hanger may be set up in the 55

position shown in Figs. 1 and 2 and the clothes hung on the different sections thereof. The spreader 14 being first moved to the position shown in full lines, the pins 15 are engaged behind the horizontal courses of the clothesline and spread the same. The pin 22^a may then be removed and the hanger swung to the position shown in dotted lines in Fig. 1 and again secured in place by the pin 22^a. When it is desired to remove the clothes, it is of course understood that the clothesline may again be swung to the position shown in Fig. 4. When the clothesline hanger is not in use, it may be removed by first removing the nut 9 and pin 22^a whereupon the hanger may be detached from the bracket and taken indoors or to some suitable place. The clothesline, with the exception of the sections 21 and 22, remains tightly stretched on the hanger and there is no danger of the line becoming entangled.

It will now be clear that I have provided a clothesline hanger which will accomplish the objects of the invention as hereinbefore stated. It will of course be understood that various changes may be made in the details of construction and arrangement of parts without departing from the spirit of my invention and that the embodiment of the invention herein disclosed is to be considered merely as illustrative and not in a limiting sense as the invention is limited only in accordance with the scope of the appended claims.

Having thus described my invention, what I claim is:

1. A clothes drier comprising a bracket adapted to be secured to a suitable support, a horizontally disposed clothespole having one end pivotally secured to said bracket and being swingable through an arc, means carried by said bracket for securing said clothespole in a plurality of positions, a pin passing through said bracket and pole and extending above and below the same, a second pin extending through said pole adjacent the opposite end thereof and disposed

in parallel relation to said first pin, a section of clothesline connecting the outer end of said pole and the upper ends of both of said pins, a second section of clothesline connecting the lower ends of said pins, a third horizontally disposed pin extending transversely of said pole and disposed adjacent the inner end thereof, a fourth pin extending transversely of said pole and positioned adjacent the outer end thereof and extending parallel to said third pin, a plurality of 10 sections of clothesline connecting said third and fourth pins, a spreader bar pivotally mounted on said pole and having portions adapted to engage said last mentioned sections of clothesline and to spread the same apart, all of said pins 15 being removable from said pole to permit disassembly of said clothes drier.

2. A clothes drier comprising a bracket adapted to be secured to a suitable support, said bracket being in the form of a casting having a pair 20 of outwardly projecting superposed spaced portions, a clothespole in the form of a metal tube having a flattened end portion which is pivotally mounted between the superposed portions of said bracket, a pair of vertically disposed pins extending through said pole, one of said pins being disposed adjacent the outer end of said pole and the other of said pins being disposed adjacent the inner end thereof and cooperating with said bracket to provide a pivotal mounting for said 30 pole, a plurality of sections of clothesline connecting said pair of pins, a pair of horizontally disposed pins extending transversely of said pole and disposed adjacent the opposite ends thereof, a plurality of sections of clothesline stretched 35 between said last mentioned pair of pins and a spreader bar pivotally mounted on said pole and having portions shaped to engage said sections of clothesline to spread the same apart, and means for securing said pole in a plurality of 40 positions.

PATRICK J. CASSERLY.
